(57) **CLAIM**

The ornamental design for an automotive steering wheel as shown and described.

DESCRIPTION

FIG. 1 is a top, front, left perspective view of an automotive steering wheel;

FIG. 2 is a bottom, rear, left perspective view of the automotive steering wheel of FIG. 1;

FIG. 3 is a front view of the automotive steering wheel of FIG. 1;

FIG. 4 is a rear view of the automotive steering wheel of FIG. 1;

FIG. 5 is a right side view of the automotive steering wheel of FIG. 1;

FIG. 6 is a left side view of the automotive steering wheel of FIG. 1;

FIG. 7 is a top view of the automotive steering wheel of FIG. 1; and,

FIG. 8 is a bottom view of the automotive steering wheel of FIG. 1.

The ornamental design which is claimed is shown in solid lines in the drawings. The broken lines of equal length dashes in the drawings depict portions of the automotive steering wheel that form no part of the claimed design. Broken lines formed by unequal length dashes (i.e., dash-dot) define bounds of the claimed design.
